GRINDING MACHINE

Jacob Decker, Cincinnati, Ohio, assignor to Cincinnati Grinders Incorporated, Cincinnati, Ohio, a corporation of Ohio

Application November 7, 1938, Serial No. 239,287

8 Claims. (Cl. 51—95)

This invention relates to grinding machines and more particularly to improvements in cross feed mechanisms therefor.

One of the objects of this invention is to provide an improved and simplified cross feed mechanism for a grinding machine.

Another object of this invention is a contrive a cross feed mechanism that may be selectively coupled for automatic operation in accordance with table traverse, or self-actuated during non-traverse of the table.

A further object of this invention is to provide means whereby a cross feed mechanism of the pick feed type may be utilized for manual operation, automatic operating during traverse grinding, or automatic operation during plunger cut grinding.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a cross sectional view through a grinding machine and shows a portion of the cross feed mechanism.

Figure 2 is an enlarged detail view of the pick feed wheel and motion transmitting connections associated therewith.

Figure 3 is a view in elevation showing the power operating mechanism for the pick feed pawl.

Figure 4 is a diagrammatic view of the control circuit for the pick feed pawl.

Referring to Figure 1 of the drawings the reference numeral 10 indicates a grinding machine table which is slidably mounted on guideways 11 and 12 for traversing movement relative to the supporting bed 13. This table carries the usual headstock 14 containing power operated means for rotating the work relative to a grinding wheel 15. The grinding wheel is rotatably mounted on a support 16 which is guided for movement on the bed 13 in a direction toward and from the axis of rotation of the work.

In grinding machines of the character described the operations performable thereon may be divided into two general classes, known as traverse grinding and plunger cut grinding. In

traverse grinding the surface to be produced on the work is longer than the grinding wheel is wide, and the table is therefore reciprocated to move the work back and forth in front of the grinding wheel. This reciprocation is effected by power means which in the present instance may consist of a hydraulic motor of either the piston and cylinder type, or of the rotary type. The former has been utilized herein and consists of the cylinder 17 and piston 18, the cylinder being fixed with the table and the piston being connected to the bed by the piston rod 19.

In order to reduce the work to size, the grinding wheel is moved toward the work a definite amount after each stroke of the table by a cross feed mechanism, and this is accomplished automatically by utilizing the moving table as a timing and actuating means.

In the plunger cut grinding the surface to be produced is equal to or less than the width of the grinding wheel whereby it becomes unnecessary to traverse the table. The grinding wheel, however, must still be fed toward the work piece, but the use of the table as a timing and actuating means is lost, and therefore other means must be provided if automatic actuation is desired.

This invention deals with improved control means for a grinding machine whereby cross feed movements may be imparted to a grinding wheel either manually, automatically in accordance with table movement for traverse grinding, or automatically at predetermined intervals by a self-actuated timing mechanism for plunger-cut grinding operations.

The mechanism for feeding the grinding wheel support 16 includes a rotatable shaft 20 which is connected through a worm and worm wheel 21 to a vertical shaft 22 having a pinion 23 which meshes with a rack bar 24 secured to the underside of the support 16. The rotatable shaft may be selectively connected in two different ratios to a shaft 25 as shown in Figures 1 and 2. A gear couple comprising gears 26 and 27 is fixed to the shaft 25. A gear 28, supported for free rotation on the shaft 20, is in constant mesh with the gear 26. A second gear 29 is splined on the shaft 20 for movement into mesh with the gear 27. The gear 29 has clutch teeth 30 on one end for interengagement with clutch teeth on the adjacent face of gear 28 whereby when the gear 29 is shifted to the left, it is withdrawn from engagement with the gear 27 and operatively connects the gear 28 to the shaft 20. When the gear 29 is shifted to the right the clutch teeth are disconnected whereby the gear 28 is rendered

ineffective during rotation of the gear 28 by the gear 27.

The shaft 25 forms part of a pick feed mechanism and has an enlarged portion 31 which is supported for rotation in a fixed bushing 32. An internal gear 33 is secured to shaft 31 for engagement with an eccentric gear 34. A second gear 35, integral with the gear 34, intermeshes with an internal gear 36 forming part of the pick feed wheel 37. The pick feed wheel is supported for rotation on a shaft 38 which has an extension 39 bearinged in the center of the shaft 31. The shaft 38 has an eccentric journal 40 which supports the gears 34 and 35 for rotation about an axis eccentric to the axis of the shaft 38. A hand wheel 41 is keyed at 42 to shaft 38 whereby upon rotation of the hand wheel the eccentric 40 is caused to move around the axis of the shaft 38 carrying the gears 34 and 35 with it.

20 If the pick feed wheel is held stationary, this will cause rotation of the gear 35, and thereby transmit motion through the gear 34 to the internal gear 33, which, being integrally connected to shaft 25, will cause rotation of the gears 26 and 27. Dependent upon the position of the shiftable gear 29, one of the gears 26 or 27 will cause rotation of the shaft 20. When the hand wheel is rotated in this manner it will effect a fine adjustment of the grinding wheel support.

25 The hand wheel 41 carries a spring pressed plunger 43 which is adapted to be inserted in a series of holes 44 formed in the pick feed wheel 37 whereby the hand wheel and the pick feed wheel may rotate as a unit and thereby effect direct rotation of the gears 26 and 27 and thereby a faster rotation of the shaft 20 per revolution of the hand wheel. By means of this mechanism the grinding wheel support may be manually adjusted at will and at different rates per revolution of the hand wheel.

30 The shiftable gear 29 is provided with an integral flange 45 which is engaged by a shifter fork 46 carried by a shifter rod 47. The rod is normally held in a position by spring 48 to hold the gear 29 in clutched relation with the gear 28. The shifter rod is moved by a spiral gear 49 supported for rotation on the end of shaft 50, the spiral gear intermeshing with spiral teeth cut in the periphery of the shifter 41. A handle 51 secured to the projection end of the shaft 50 serves as means for rotating the same.

35 For automatic power operation of the pick feed wheel there is provided a pickfeed lever 52 which is supported for free rotation on the hub of the bushing 32 and the upper end of this lever is provided with a pick feed pawl 53 for engagement with the teeth 54 formed on the periphery of the pick feed wheel 36. The hub 55 of the lever, Figure 3, has a series of gear teeth 56 formed on the periphery thereof for interengagement with gear teeth 57 formed on the end of a pivoted lever 58. The lever 58 is fixed with a shaft 59 which in turn has a fixed lever 60 carrying a follower roller 61. The follower roller is positioned to engage a cam surface 62 formed on the periphery of a hydraulically actuated piston 63. The piston is reciprocally mounted in a cylinder 64. The cam 62 is formed with a peak 65 midway of its length whereby as the piston moves toward its center position from either side it will cause clockwise rotation of the lever 60 and counterclockwise rotation of the pick feed lever 52. A spring pressed plunger 66 acts on the lever 60 to maintain the

roller in contact with the cam and to urge the lever 52 to its return position.

5 In order to vary the length of the pick feed, an adjustable return stop is provided, comprising a stop screw 67 which is threaded in a fixed lug 68. A lock nut 69 threaded on the screw 67 serves to secure the parts in a fixed position. It will be apparent that by adjusting the stop screw 67 to the left, as viewed in the drawings, the lever 52 will be limited in its return movement, and furthermore, the roller 61 will be limited in its return movement toward the cam 62 and this provides a variable amount of lost motion between the piston 63 and the roller 61 before the same is actuated. In this way, the piston may be caused to effect variable amounts of movement to the pick feed lever.

10 A ratchet dog 70 has been provided for automatically stopping the pick feed action and this dog is carried by and movable with the pick feed wheel 36.

15 The dog has a head portion 71 in which is formed a T-slot 72 which embraces the T-shaped rim of the pick feed wheel 36. Axially movable pin 73 serves to lock the ratchet dog in any adjusted position around the periphery of the wheel 36.

20 An independently operating hydraulic circuit has been provided for reciprocating the piston 63 to effect automatic infeed of the grinding wheel 30 for plunge cut grinding purposes, when the table is stationary. This circuit includes means for imparting to the piston hydraulic pulsations or impulses alternately in opposite directions so that the piston 63 operates as a pulsator having a relatively high speed oscillation for producing the successive incremental pick feed actions for relative infeed of work and grinding wheel. The opposite ends of the cylinder 64 are connected by hydraulic channels 74 and 75, Figure 4, to ports 76 and 77 respectively of a reversing valve 78. This valve has a pressure port 79 which is connected by channel 80 to port 81 of a rotatable start and stop valve 82. A pump 83 having an intake 84, through which fluid is withdrawn from reservoir 85 has a delivery channel 86 which is connected to port 87 of valve 82. When the plunger 88 of this valve is rotated in a clockwise direction from the position shown in Figure 4, the pressure port 87 is connected to port 81, whereby the port 79 of the reversing valve is supplied with pressure.

25 The reversing valve has a plunger 89 on which is formed a central spool 90 and end spools 91 and 92, resulting in intermediate annular grooves 93 and 94. When the plunger 89 is in the position shown, the pressure port 79 is connected to port 76 whereby fluid will flow to the left end of cylinder 64 to cause the same to move toward the right and the fluid in the right hand end of the cylinder will return to reservoir through port 77, annular groove 94 and port 95 to channel 86. This channel terminates in port 97 of the stop valve which will be connected through port 98 to return channel 88.

30 The reversing valve plunger is automatically power shifted at predetermined intervals under control of a pilot valve 100 and a timing mechanism which governs the shifting of the pilot valve plunger 101. The pilot valve has a pair 70 of ports 102 and 103 which are alternately connected by grooves 104 and 105 in plunger 101 with a pressure port 106. The ports 102 and 103 are connected by channels 107 and 108 to opposite ends of the reversing valve. Thus, when 75

the plunger 101 is in its left hand position, as shown in the drawings, the pressure port 106 is connected to port 103 whereby the reversing valve plunger is shifted to the right, and when 5 the port 106 is connected to the port 102 the reversing valve plunger is shifted to the left. When the port 103 is connected to pressure, the port 102 is connected by the annular groove 104 to the exhaust line 109 and when the port 102 10 is connected to pressure the port 103 is connected to the exhaust line 96.

The pilot valve plunger is, in turn, hydraulically shifted in accordance with the pressure condition in channels 74 and 75. For instance, 15 with the stop valve 88 in a running position, the channel 74 would be under pressure and the channel 75 connected to exhaust. The pressure in channel 74 is now utilized to effect shifting of the pilot valve and this is effected by providing 20 a shuttle valve 110 which has spring pressed plunger 111 normally held in a position to disconnect the port 112 from the port 113 which is connected by a branch line 114 to the channel 74. The pressure fluid entering channel 114 and 25 port 113 urges the plunger 111 downward against the resistance of spring 115, uncovering the port 112, whereby the pressure fluid acts on the end of plunger 101 to shift the same toward the right. Since the right hand end of the pilot 30 valve 100 is filled with fluid, due to previous operation, this fluid must be exhausted in order that the plunger may move.

A second shuttle valve 116 connected to the right hand end of the pilot valve also has a 35 spring pressed plunger 117 which, in its normal position, connects port 118 to port 119. The port 119 is connected by channel 120 to port 121 of an adjustable delay valve 122. This valve has a plunger 123 in which is formed a series of 40 V-shaped grooves 124 to restrict the flow from port 121 to an exhaust port 125. By adjusting the position of this valve by the threaded plunger 126, the rate of escape of fluid from the right hand end of the pilot valve can be adjusted to 45 vary the time which it will take the pilot valve plunger to move toward the right a sufficient distance to interconnect the pressure port 106 with port 102. It should now be evident that after the pick feed mechanism has been actuated, the fluid pressure in channel 74 continues 50 to act to shift the pilot valve plunger, but this movement is retarded by the delay valve so that a predetermined time interval exists before the reversing valve is again shifted to effect the next 55 actuation of the pick feed mechanism.

The same thing is true when the channel 75 is put under pressure because the channel 75 has a branch line 127 which is connected to port 128 of shuttle valve 116 whereby the plunger of 60 this valve will move downward to interconnect port 128 to port 118. The plunger 111 of shuttle valve 110 will be in a position to connect port 112 to port 129 which, in turn, is connected by channel 130 to the delay valve port 121. It will now 65 be apparent that by means of this self-actuating circuit, automatic actuation of the pick feed mechanism may be obtained.

Means are also shown, Figure 4, whereby the pick feed piston may be controlled from the table 70 during traverse grinding. The channels 74 and 75 have branch connections 131 and 132 to ports 133 and 134 of a selector valve 135, having rotatable valve portions 1351 and 1352. The selector valve serves to connect ports 133 and 134 to ports 75 136 and 137 respectively which have branch lines

138 and 139 connected to motor supply lines 140 and 141 for the table actuating motor. The channels 140 and 141 are adapted to be alternately put under pressure and exhaust by suitably known means, to cause reciprocation of the piston 18 in the cylinder 17. The selector valve has additional valve portions 142 and 143 whereby when the valve plunger is positioned to connect the ports 133 and 134 to ports 136 and 137, the motor channels 140 and 141 are connected to 10 lines 144 and 145 leading to the table motor. The stop valve plunger 88 and the selector valve plunger are integral whereby in one position the self-actuating circuit is connected to pressure, the ports 133 and 134 are closed and the table 15 cylinder 17 is disconnected from the motor supply lines 140 and 141. In the other position the source of pressure is disconnected from the self-actuating circuit, and the pick feed cylinder 64 and the cylinder 17 are connected in parallel to 20 the motor supply lines 140 and 141 whereby every time the pressure is reversed in these channels the pick feed piston is shifted.

There has thus been provided an improved control circuit for the infeed mechanism of a 25 grinding machine whereby automatic pick feed may be obtained regardless of the method of grinding.

I claim:

1. In a grinding machine of the type embodying a relatively traversable work support, and wheel head and means including a hydraulic piston and cylinder mechanism for effecting said traverse, means for controlling relative movement of said support and wheel head in a feeding direction, including a source of hydraulic medium under pressure, a first hydraulic conduit system couplable with the traversing piston and cylinder, a feed mechanism, a second hydraulic conduit system coupled with the feed mechanism, a third 35 hydraulic conduit system including an independent, reversing system for producing alternate pulsations or impulses in opposite directions in the system, and selector means operable to couple the feed control mechanism in parallel with the first hydraulic system or in series with the second 40 hydraulic system whereby the feed mechanism may be selectively operated by reversals of the traversing system or by intermittent alternate movements in accordance with the impulses of 45 the series coupled system.

2. In a grinding machine of the type embodying a relatively traversable work support and wheel head and means including a hydraulic piston and cylinder mechanism for effecting said 55 traverse, means for controlling relative movement of said support and wheel head in a feeding direction, including a source of hydraulic medium under pressure, a first hydraulic conduit system couplable with the traversing piston and cylinder, a feed mechanism, a second hydraulic conduit system coupled with the feed mechanism, a third 60 hydraulic conduit system including an independent, reversing system for producing alternate pulsations or impulses in opposite directions in the system, selector means operable to couple the feed control mechanism in parallel with the first hydraulic system or in series with the second 65 hydraulic system whereby the feed mechanism may be selectively operated by reversals of the traversing system or by intermittent alternate movements in accordance with the impulses of the series coupled system, and means for variably determining the frequency of said impulses and 70 75

thus the rate of actuation of the feeding mechanism.

3. An infeed control mechanism for a machine tool including a pulsatable member and a hydraulic circuit for determining the pulsations thereof including a source of hydraulic medium under pressure, a reversing valve variably positionable to determine the coupling of the source of pressure with the pulsatable member, a pilot valve 10 shiftable to effect opposite positionings of said reversing valve, means for controlling the positioning of the pilot valve including a branch hydraulic circuit coupled in parallel with the pulsator and a pressure actuated valve shiftable by 15 pressure in said branch circuit for operatively coupling the circuit with the pilot valve to initiate opposite positioning of the reverser, and means for variably determining the rate of movement of the pilot valve and thus the time interval of the 20 pulsations.

4. An infeed control mechanism for a machine tool including a pulsatable member and a hydraulic circuit for determining the pulsations thereof including a source of hydraulic medium under 25 pressure, a reversing valve variably positionable to determine the coupling of the source of pressure with the pulsatable member, a pilot valve shiftable to effect opposite positionings of said reversing valve, means for controlling the positioning of the pilot valve including a branch 30 hydraulic circuit coupled in parallel with the pulsator and a pressure actuated valve shiftable by pressure in said branch circuit for operatively coupling the circuit with the pilot valve to initiate 35 opposite positioning of the reverser, means for variably determining the rate of movement of the pilot valve and thus the time interval of the pulsations, and additional valve means for determining the operative coupling of the pilot 40 valve with said rate determinator.

5. In a machine tool comprising a pair of support members mounted for relative feeding movement and means for producing said movement including a pulsator and a hydraulic mechanism for determining the pulsations thereof including a source of hydraulic medium under pressure, a reversing valve for effecting alternate directional couplings of the medium with the pulsator, a pilot valve for determining the position of the reversing valve coupled in parallel 50 with the pulsator whereby movement of the reversing valve will react on the pilot valve to effect a reversal thereof, said pilot valve including terminal piston portions, an adjustable delay device, conduits coupling the piston portions of the pilot valve in parallel with the delay device, and independent valve members interposed in the conduits connecting the pulsator and pilot valve pistons and actuatable by existence of pressure in 55 the related conduit for disconnecting the associated pilot valve piston as respects the delay device, substantially as and for the purpose described.

6. In a machine tool comprising a pair of support members mounted for relative feeding movement and means for producing said movement including a pulsator and a hydraulic mechanism for determining the pulsations thereof including a source of hydraulic medium under 65 pressure, a reversing valve for effecting alternate directional couplings of the medium with the pulsator, a pilot valve for determining the position of the reversing valve coupled in parallel with the pulsator whereby movement of the re-

versing valve will react on the pilot valve to effect a reversal thereof, said pilot valve including terminal piston portions, an adjustable delay device, conduits coupling the piston portions of the pilot valve in parallel with the delay device, 5 valve members disposed adjacent the termini of the pilot valve, and means resiliently urging said valve members in position to couple the pilot valve pistons with the delay device, said valves having piston portions individually actuatable by pressure in the coupled end of the pulsator whereby said valves will be individually shifted by said existing pressure to disconnect the delay device and admit pressure by way of the valve to react on the associated pilot valve piston portion. 10 15

7. An infeed control mechanism of the character for effecting substantially continuous relative infeed of work and grinding wheel, including a pulsatable piston, a pick feed mechanism actuatable by the pulsations thereof, means for effecting pulsations of said piston including a pressure source, independent pilot and reversing valves, branch pressure conduits coupled with the respective valves, potential pressure conduits interconnecting the pilot and reverser valves, 25 additional conduits interconnecting the reverser valve and the pulsator, a cylinder enclosing the pilot valve, a pair of discharge lines extending from the termini of the pilot valve cylinder to receive exhaust fluid therefrom, individual control valves for the pilot cylinder exhaust conduits, conduits individually coupling said valves at opposite ends of the pilot cylinder in parallel with the opposite ends of the pulsator, said valves having piston portions actuatable by pressure in 30 said parallel couplings for shifting the valves whereby pressure in either end of the pulsator will shift the associate valve to close the reservoir connection at one end of the pilot valve cylinder and admit said coupled pressure into the 35 cylinder for shifting of the pilot valve. 40

8. An infeed control mechanism of the character for effecting substantially continuous relative infeed of work and grinding wheel, including a pulsatable piston, a pick feed mechanism 45 actuatable by the pulsations thereof, means for effecting pulsations of said piston including a pressure source, independent pilot and reversing valves, branch pressure conduits coupled with the respective valves, potential pressure conduits interconnecting the pilot and reverser valves, additional conduits interconnecting the reverser valve and the pulsator, a cylinder enclosing the pilot valve, a pair of discharge lines extending from the termini of the pilot valve cylinder to receive exhaust fluid therefrom, individual control valves for the pilot cylinder exhaust conduits, conduits individually coupling said valves at opposite ends of the pilot cylinder in parallel with the opposite ends of the pulsator, said valves having piston portions actuatable by pressure in 50 said parallel couplings for shifting the valves whereby pressure in either end of the pulsator will shift the associate valve to close the reservoir connection at one end of the pilot valve cylinder and admit said coupled pressure into the cylinder for shifting of the pilot valve, and an adjustable delay means in the exhaust conduits for the pilot valve, whereby said means will variably determine the rate of movement of the pilot valve and determine the time interval between 55 positive actuations of the reverse valve. 60 65 70 75
